This invention is concerned with power interrupting systems for interrupting electric high-voltage circuits.

Generally power circuit breakers are used for interrupting electric high-voltage circuits. There is, however, no power circuit breaker known which is capable of performing entirely satisfactorily on occurrence of various different interrupting conditions such as, interrupting major fault currents, or short-circuit currents, and interrupting relatively small capacitive line charging currents.

It is, therefore, the principal object of this invention to provide a power interrupting system for high-voltage circuits which lends itself equally well to various different interrupting conditions including interrupting major fault currents and interrupting relatively small capacitive line charging currents.

Another object of this invention is to provide composite circuit interrupting devices comprising interrupting means which lend themselves particularly well to the interruption of major fault currents, and interrupting means which lend themselves particularly well to the interruption of relatively small capacitive line charging currents, in which interrupting devices both types of interrupting means are automatically controlled in such a fashion that the interrupting task at hand is performed by the interrupting means which is particularly adapted, or best suited, to perform that task, while the other interrupting means not particularly adapted and not best suited to perform that task does not take any part in it.

The interrupting performance of a circuit interrupting device depends primarily upon the arc voltage which it generates during the arcing time and upon the rate of dielectric recovery of the arc gap following arc extinction. These two qualities depend, in turn, upon the particular means used in any piece of circuit interrupting equipment for effecting interruption of the circuit to be interrupted. Because of their particular mechanism of circuit interruption circuit breakers using oil as an arc quenching medium, i.e. tank type oil circuit breakers and oil-poor circuit breakers, lend themselves well to the interruption of major fault currents including short-circuit currents. Such circuit breakers are generally not capable of effectively interrupting the capacitive currents which occur when disconnecting large capacitor banks, or on dropping long transmission or distribution lines. There is a tendency of restrikes and of build-up of dangerous overvoltages when oil circuit breakers are used for interrupting relatively small capacitive currents. Vacuum circuit breakers are not well suited for interruption of major fault currents because their ability to dissipate heat is relatively limited, and because interruption of very large currents involves the danger of generation of excessive amounts of metal vapors within the evacuated envelopes housing the contacts of vacuum circuit breakers. Vacuum circuit breakers have, however, performance characteristics which make this type of circuit breakers particularly suitable for interrupting relatively low substantially capacitive or leading currents. The same is also true in regard to axial air blast circuit breakers, i.e. such circuit breakers have also performance characteristics which make them particularly suited for interrupting relatively small capacitive or leading currents.

2

It is, therefore, another object of this invention to provide combinations of circuit breakers which use oil as an interrupting medium, such as tank type oil circuit breakers and oil-poor circuit breakers, or other circuit breakers having similar interrupting performance characteristics, i.e. any kind of major fault current interrupting devices, and of vacuum circuit breakers, or axial air blast circuit breakers, or other circuit breakers having similar interrupting performance characteristics, i.e. any kind of capacitive current interrupting devices, which combinations of interrupting devices are under the control of a sensing means which determines automatically which of the two associated devices ought to perform a specific interrupting task, and which of the two associated interrupting devices should be kept from performing a specific interrupting task for which it is not particularly well suited.

It is possible for the above mentioned ends to use combinations of major fault current interrupting devices, and of capacitive current interrupting devices, wherein the individual devices are either serially connected into the high-voltage circuit to be interrupted, or are connected in parallel into that circuit. In case of a series connection the circuit breaker which is particularly well suited to perform the required interrupting task is initially caused to form one or more serially related circuit interrupting breaks. Only after complete interruption of the circuit under consideration is the second circuit breaker or interrupting device caused to open. Since the circuit is interrupted by the time the contacts separate which form part of the circuit breaker or interrupting device which has not been required to perform a particular circuit interrupting task, that circuit breaker or interrupting device operates as a mere disconnect, interposing additional circuit insulation into a circuit previously interrupted by the operation of another piece of equipment.

Where two power circuit breakers, or other current interrupting devices, having different interrupting performance characteristics are arranged in parallel in the high-voltage circuit to be interrupted, the sequence of operation is different from the case of serially related power circuit breakers, or other current interrupting devices. In the case of parallel connection the circuit breakers or other current interrupting device not particularly suited for the interrupting task at hand is caused to open first, and thereafter the circuit breaker or other current interrupting device particularly suited for the interrupting task at hand is caused to open. Hence there is no voltage across the contacts of the circuit breaker or other current interrupting device which opens first, the contacts of this circuit breaker or other circuit interrupting device being shunted at the time they part by the engaging contacts of the other circuit breaker or current interrupting device.

It is apparent from the foregoing that there is a predetermined sequence of opening of circuit breakers, or other current interrupting devices, in the aforementioned case of series connection and in the aforementioned case of parallel connection. The sequence is, however, different in both cases. In the case of serially connected circuit breakers, or other current interrupting devices, the device most appropriate for the interrupting task at hand opens first and the interrupting device less appropriate for the interrupting task at hand opens last. In the case of circuit breakers, or other current interrupting devices which are connected in parallel into the circuit to be interrupted the circuit breaker, or other current interrupting device, which is less appropriate for the interrupting task at hand opens first and it is followed by opening of the circuit breaker, or other current interrupting device, which is most appropriate for the interrupting task at hand.

The "brain" determining which of the two possible sequences of circuit breaker operation ought to be adopted

in any specific instance may be a phase-angle sensing device. The phase-angle sensing device may be arranged at substantially the same potential as the high-voltage circuit to be interrupted. Preferably the phase-angle sensing device operates at a lower voltage level since it must generally be operatively related to other control equipment which is on a lower voltage level. A current transformer and a potential transformer will generally be applied to energize the phase-angle sensing device. Where the circuit voltage is particularly high the phase-angle sensing device may be energized from the high-voltage line by the intermediary of a plurality of cascaded insulating transformers.

The phase-angle sensing device will generally take the form of a Tuma phase meter, or an equivalent type of phase-angle meter. Such an instrument comprises a fixed coil and two movable coils forming a single movable system pivoted in the field due to the fixed coil. Both movable coils are inclined to each other at an angle of 90 degrees. The current in one of the movable coils is supposed to be in phase with the applied voltage, and the current in the other of the movable coils is supposed to be in quadrature with the voltage. Tuma phase meters and related phase-angle sensing means used according to this invention as a means for determining the sequence of operation to be imposed upon a plurality of circuit breakers are well known in the art and, therefore, do not need to be described here in detail (see, for instance, Frank E. Laws, Electrical Measurements, New York and London 1938 at page 545 and following).

For a better understanding of the present invention reference may be had to the accompanying drawing diagrammatically illustrating a preferred embodiment of the invention.

Referring now to the drawing, numeral 1 has been applied to indicate two serially related pairs of cooperating separable contacts forming part of a circuit breaker particularly adapted to interrupt major fault currents, e.g. a circuit breaker wherein oil is used as the arc-quenching medium. Reference numeral 2 has been applied to indicate two serially related pairs of cooperating separable contacts forming part of a circuit breaker particularly adapted to interrupt relatively small capacitive currents. This circuit breaker may be a vacuum circuit breaker, or an axial air blast circuit breaker. The number of serially related cooperating separable contacts in each of the two circuit breakers depends primarily upon the system voltage of the electric system in which the composite circuit breaker is to be applied, and increases with increasing system voltage. Reference numeral 4 has been applied to indicate the incoming line and the outgoing line, and it will be apparent that the two power circuit breakers including the pairs of contacts 1, 1 and 2, 2 are arranged in parallel in the circuit to be controlled. An equipotential conductor conductively interconnects points between serially related pairs of contacts 1, 1 and 2, 2 of the two circuit breakers. Both circuit breakers are shunted by a voltage distribution controlling shunt extending across both circuit breakers or current interrupting devices and conductively connected to the aforementioned equipotential conductor. In the embodiment of the invention shown in the drawing the voltage distribution shunt includes a pair of capacitors 3. These might be replaced, if desired, by ohmic resistors appropriate for the purpose of voltage control in both circuit breaker structures. It will be apparent from the foregoing that a single voltage distribution controlling shunt controls the voltage distribution across both circuit breakers, or current interrupting devices, and thus controls the recovery voltage which appears across each of the breaks formed between contact means 1, 1 and 2, 2 and the distribution or apportionment of the aggregate recovery voltage across either of the two serially related breaks between contact means 1, 1 and 2, 2. The equipotential conductor conductively interconnecting points between serially related pairs of contacts

1, 1 and 2, 2 of the two circuit breakers, or current interrupting devices makes sure that the same portion of the total recovery voltage appears across corresponding breaks of the left circuit breaker, or current interrupting device, 5 and the right circuit breaker, or current interrupting device. Reference numerals 5 and 6 indicate the points at which line 4 is connected to the composite circuit breaker structure. The current transformer 7 and the voltage transformer 9 are energized by the current flowing in line

10 4. The current transformer 7 energizes the current winding in the phase-angle sensing system or phase meter 8, and the voltage transformer 9 energizes the voltage winding in the phase-angle sensing system or phase meter 8. Phase-angle sensing device 8 controls an auxiliary control valve, or pilot valve, adapted to admit an operating impulse of air under pressure to the change-over valve 11 whenever the current in line 4 is a capacitive current, or a leading current. Reference numeral 12 has been applied to indicate a tripping means such as a circuit breaker tripping magnet. Tripping means 12 may be energized either in response to a manually given opening command or in response to an opening command given by a fault current responsive relay. Whenever tripping means 12 is energized a tripping valve forming an integral part of tripping means 12 is opened and admits air under pressure to the changeover valve system 11. The latter has two positions. In one of the two positions air under pressure is admitted sequentially to the pneumatically operated control valves 14, 13. The sequence is reversed if change-over valve 11 20 is moved to the other position thereof, i.e. in that case operation of valve 13 precedes that of valve 14. Each of the two current interrupting devices including cooperating contacts 1, 1 and 2, 2 is provided with a contact separating fluid motor or pneumatic motor (not shown). The fluid motor for opening the right interrupting device is under the control of control valve 13 and the fluid motor for opening the left interrupting device is under the control of control valve 14.

30 If a manual tripping impulse is sent to the tripping means 12, or if the latter is energized by the action of a fault current responsive relay, the current flowing in line 4 should be interrupted by the circuit breaker comprising the serially related pairs of contacts 1, 1, and the circuit breaker comprising the pairs of serially related contacts 2, 2 should not participate in the process of current interruption. To achieve this end change-over valve 11 is normally maintained in such a position that air under pressure is admitted to valve 14 at a point of time preceding the point of time at which air under pressure is admitted to valve 13. Consequently the pair of contacts 2, 2 will

40 open while being shunted by the pairs of contacts 1, 1, resulting in a virtually arcless interruption of the current path through the left circuit breaker. If a capacitive or leading current flows through line 4 the phase-angle sensing system 8 moves from its normal position to another position indicative of the presence of a capacitive or leading current. This causes operation or opening of the auxiliary control valve or pilot valve 10, admitting air under pressure to the operating means of change-over valve 11, causing the latter to be moved from its normal position giving operating precedence to the left circuit breaker including contact means 2, 2 to its capacitive current interrupting position giving precedence to the right circuit breaker including contact means 1, 1. If change-over valve 11 is in the latter position air under pressure is admitted to control valve 13 before air under pressure is admitted to control valve 14, and consequently the right circuit breaker comprising contact means 1, 1 opens before the left circuit breaker comprising contact means 2, 2 opens. Hence the contact means 1, 1 of the right circuit breaker are shunted by the contact means 2, 2 of the left circuit breaker while the former is being opened. Thus the capacitive current is interrupted by the action of the left circuit breaker comprising contact means 2, 2, the right circuit breaker comprising contact means 1, 1 not sharing

in the performance of an interrupting tasks for which it is not well suited.

Change-over valve 11 is normally held in the position giving opening precedence to the left circuit breaker, or biased to that position. The position of change-over valve 11 is changed to the position giving opening precedence to the right circuit breaker comprising contact means 1, 1 only upon occurrence of a capacitive current in line 4. Thus there is no delay in interrupting major fault currents or short circuit currents, the system being always ready to perform this paramount duty, and only changing to the performance of its duty of interrupting relatively small capacitive currents when an occasion to perform such particular duty arises.

Since the circuit breaker comprising contact means 2, 2 is, or may be, capable of interrupting load currents and small overload currents in addition to interrupting capacitive currents, the right circuit breaker comprising contact means 1, 1 may be relieved of its task of interrupting load and small overload currents. In other words, the right circuit breaker comprising contact means 1, 1 may be designed for the sole purpose of interrupting major fault currents, and thus its design may be considerably simplified. Under such conditions the change-over valve 11 may normally be held in the position giving precedence to the opening operation of the right circuit breaker comprising contact means 1, 1 and be shifted on occurrence of a major fault current by an appropriate sensing device responsive to a parameter of the current flowing in line 4 to the opposite opening sequence position thereof.

It will be seen from the foregoing that the particular embodiment of the invention which I have described presupposes the presence of a pneumatic control and of a pneumatic contact opening system for the major fault current circuit breaker and for the capacitive current circuit breaker. The presence of such a control system and such a contact opening system has been assumed to better illustrate the invention, but the invention is not limited to the presence of such a control system and contact opening system. Both circuit breakers might be controlled by a substantially conventional electric circuit breaker control system which may be combined with two appropriate fluid motors to effect sequential separation of pairs of cooperating contacts in either of both circuit breakers. In that instance the change-over valve 11 has to be replaced by a change-over switch having two positions governing the sequence to be given to the opening operations of the two circuit breakers. Such a change-over switch may be, in turn, under the control of phase-angle sensing instrument 8.

Having disclosed a preferred way of carrying my invention into effect, it is desired that the same not be limited to the particular arrangement of parts disclosed. It will be obvious to any person skilled in the art that many modifications and changes may be made without departing from the broad spirit and scope of the invention. Therefore it is desired that the invention be interpreted as broadly as possible and that it be limited only as required by the prior state of the art.

I claim as my invention:

1. A power interrupting system for interrupting electric high-voltage circuits comprising in combination:

- (a) an electric high-voltage circuit;
- (b) a pair of power circuit breakers having different interrupting performance characteristics included in said circuit, said pair of circuit breakers including a first circuit breaker particularly adapted to interrupt major fault currents and said pair of circuit breakers including a second circuit breaker particularly adapted to interrupt relatively small currents including capacitive currents;
- (c) tripping means for initiating opening of said pair of circuit breakers;
- (d) change-over means having two positions for selectively determining the sequence of opening of said

first circuit breaker and of said second circuit breaker in response to said tripping means; and

- (e) sensing means under the control of the current flowing in said circuit for operating said change-over means in response to a parameter of said current.

2. A power interrupting system for interrupting electric high-voltage circuits comprising in combination:

- (a) an electric high-voltage circuit;
- (b) a plurality of power circuit breakers having different interrupting performance characteristics included in said circuit;
- (c) tripping means for initiating opening of said plurality of circuit breakers;
- (d) phase-angle sensing means operatively related to said circuit for determining the phase-angle therein; and
- (e) means responsive to said tripping means and also responsive to said phase-angle sensing means for establishing a predetermined sequence of opening of said plurality of power circuit breakers in response to the phase-angle prevailing in said circuit.

3. A power interrupting system as specified in claim 2 wherein said plurality of circuit breakers includes a circuit breaker wherein oil is used as an arc-quenching medium and a vacuum circuit breaker.

4. A power interrupting system as specified in claim 2 wherein said plurality of circuit breakers includes a circuit breaker wherein oil is used as an arc-quenching medium and an axial air blast circuit breaker.

5. A power interrupting system as specified in claim 2 wherein said phase-angle sensing means is arranged at substantially the same potential as said high-voltage circuit.

6. A power interrupting system for interrupting electric high-voltage circuits comprising in combination:

- (a) an electric high-voltage circuit;
- (b) a plurality of break-forming current interrupting devices having different interrupting performance characteristics included in said circuit;
- (c) tripping means for initiating opening of said plurality of interrupting devices;
- (d) a current transformer operatively related to said circuit;
- (e) a potential transformer operatively related to said circuit;
- (f) a phase-angle meter operatively related to said current transformer and to said voltage transformer to indicate the phase-angle in said circuit; and
- (g) means responsive to said tripping means and also responsive to said phase-angle meter for establishing a predetermined sequence of opening of said plurality of interrupting devices in response to the phase-angle prevailing in said circuit.

7. A power interrupting system for interrupting electric high-voltage circuits comprising in combination:

- (a) an electric high-voltage circuit;
- (b) a pair of break-forming pneumatically operated current interrupting devices having different interrupting performance characteristics included in said circuit;
- (c) a pair of pneumatically operated control valves each operatively related to the contact separating means of one of said pair of interrupting devices;
- (d) tripping means for initiating opening of said plurality of interrupting devices;
- (e) a tripping valve under the control of said tripping means for admitting air under pressure to said pair of control valves in response to operation of said tripping means;
- (f) a pneumatically operated change-over valve supplied with air under pressure from said tripping valve and admitting air under pressure to said pair of control valves, said change-over valve including means for varying the sequence of admission of air under pressure to each of said pair of control valves;

- 7
- (g) phase-angle sensing means operatively related to said circuit; and
- (h) an auxiliary control valve under the control of said phase-angle sensing means for admitting air under pressure to said change-over valve to operate said change-over valve in response to the phase-angle prevailing in said circuit. 5
8. A power interrupting system for interrupting electric high voltage circuits comprising in combination:
- (a) an electric high-voltage circuit;
- (b) a pair of break-forming current interrupting devices having different interrupting performance characteristics arranged in parallel in said circuit, said pair of interrupting devices including a first interrupting device particularly adapted to interrupt major fault currents and said pair of interrupting devices including a second interrupting device particularly adapted to interrupt relatively small currents including capacitive currents; 10
- (c) tripping means for initiating opening of said pair of interrupting devices;
- (d) control means having a first position and having a second position and being adapted when in said first position thereof to cause sequential opening of said first interrupting device and of said second interrupting device, and said control means being adapted when in said second position thereof to cause sequential opening of said second interrupting device and of said first interrupting device; and
- (e) sensing means under the control of the current flowing in said circuit for operating said control means in response to a parameter of said current. 30
9. A power interrupting system for interrupting electric high-voltage circuits comprising in combination:
- (a) an electric high-voltage circuit;
- (b) a pair of break-forming current interrupting devices having different interrupting performance characteristics arranged in parallel in said circuit, said pair of interrupting devices including a major fault current interrupting device and a capacitive current interrupting device; 35
- (c) tripping means for initiating opening of said pair of interrupting devices;
- (d) control means having a first position and a second position and being adapted when in said first position thereof to cause sequential opening of said capacitive current interrupting device and of said major fault current interrupting device in response to operation of said tripping means, and said control means being adapted when in said second position thereof to cause sequential opening of said major fault current interrupting device and of said capacitive current interrupting device in response to operation of said tripping means; and
- (e) phase-sensing means for determining the phase-angle in said circuit, said sensing means being operatively related to said control means to shift said control means from said first position thereof to said second position thereof upon occurrence of a capacitive current in said circuit. 50
10. A power interrupting system as specified in claim 9 wherein said capacitive current interrupting device is a vacuum circuit breaker. 60
11. A power interrupting system as specified in claim 9 wherein said capacitive current interrupting device is an axial blast air blast circuit breaker. 65
12. A power interrupting system for interrupting electric high voltage circuits comprising in combination:
- (a) an electric high-voltage circuit;
- (b) a pair of break-forming current-interrupting devices having different interrupting performance characteristics arranged in parallel in said circuit, said interrupting devices including a major fault current interrupting device and a capacitive current interrupting device, and each of said pair of interrupting 70
- devices including serially related pairs of separable contacts to form series breaks upon separation of said pairs of contacts;
- (c) equipotential conductor means conductively interconnecting points between serially related pairs of contacts of said pair of interrupting devices;
- (d) voltage distribution controlling shunt means extending across said pair of interrupting devices and conductively connected to said equipotential conductor means;
- (e) tripping means for initiating opening of said pair of interrupting devices;
- (f) control means having a first position and a second position and being adapted when in said first position to cause sequential opening of said capacitive current interrupting device and of said major fault current interrupting device in response to operation of said tripping means, and said control means being adapted when in said second position thereof to cause sequential opening of said major fault current interrupting device and of said capacitive current interrupting device; and
- (g) phase-sensing means adapted to sense the phase angle in said circuit operatively related to said control means to shift said control means from said first position thereof to said second position thereof upon occurrence of a capacitive current in said circuit. 75
13. A power interrupting system for interrupting electric high-voltage circuits comprising in combination:
- (a) an electric high-voltage circuit;
- (b) a pair of break-forming current interrupting devices having different interrupting performance characteristics arranged in parallel in said circuit, said pair of interrupting devices including a major fault current interrupting device and a capacitive current interrupting device;
- (c) tripping means for initiating opening of said pair of current interrupting devices;
- (d) control means having a first position and a second position and being adapted when in said first position thereof to cause sequential opening of said capacitive current interrupting device and of said major fault current interrupting device in response to operation of said tripping means, and said control means being adapted to cause when in said second position thereof sequential opening of said major fault current interrupting device and of said capacitive current interrupting device;
- (e) a current transformer operatively related to said circuit;
- (f) a potential transformer operatively related to said circuit; and
- (g) a phase-angle meter connected to said current transformer and to said potential transformer to indicate the phase-angle in said circuit, said meter being operatively related to said control means to shift said control means from said first position thereof to said second position thereof upon occurrence of a capacitive current in said circuit. 80
14. A power interrupting system for interrupting electric high-voltage circuits comprising in combination:
- (a) an electric high-voltage circuit;
- (b) a pair of break-forming current interrupting devices having different performance characteristics arranged in parallel in said circuit, said pair of current interrupting devices including a first current interrupting device particularly adapted to interrupt major fault currents and said pair of current interrupting devices including a second current interrupting device particularly adapted to interrupt relatively small currents including capacitive currents;
- (c) tripping means for initiating opening of said pair of current interrupting devices;
- (d) variable means for controlling and changing the

- sequence of opening of said pair of current interrupting devices; and
- (e) sensing means under the control of electric currents flowing in said circuit operatively related to said opening sequence controlling and changing means to vary the position thereof.
15. A power interrupting system for interrupting electric high-voltage circuits comprising in combination:
- (a) an electric high-voltage circuit;
- (b) a pair of break-forming current interrupting devices having different performance characteristics arranged in parallel in said circuit, said pair of current interrupting devices including a first current interrupting device particularly adapted to interrupt major fault currents and said pair of current interrupting devices including a second current interrupting device particularly adapted to interrupt relatively small currents including capacitive currents;
- (c) tripping means for initiating opening of said pair of current interrupting devices;
- (d) variable means for controlling and changing the

5

10

15

20

sequence of opening of said pair of current interrupting devices, said variable means being normally maintained in a position causing opening of said first current interrupting device to precede opening of said second current interrupting device; and

(e) sensing means affected by the flow of current in said circuit adapted to vary said sequence controlling and changing means to reverse the sequence of opening of said first current interrupting device and of opening said second current interrupting device.
